UNITED STATES PATENT OFFICE.

ERNEST J. KNABE, JR., OF BALTIMORE, MARYLAND, ASSIGNOR TO
WILLIAM KNABE & COMPANY MANUFACTURING COMPANY, OF
BALTIMORE, MARYLAND, A CORPORATION OF MARYLAND.

SELF-PLAYING PIANO.

No. 839,602.

Specification of Letters Patent.

Patented Dec. 25, 1906.

Application filed November 15, 1905. Serial No. 287,516.

To all whom it may concern:

Be it known that I, ERNEST J. KNABE, Jr., a citizen of the United States, residing at Baltimore, in the State of Maryland, have invented certain new and useful Improvements in Self-Playing Pianos; and I do hereby declare the following to be a full, clear, and exact description of the invention, such as will enable others skilled in the art to 10 which it appertains to make and use the same.

My invention relates to improvements in self-playing pianos; and the object of my invention is to provide simple means for counterbalancing the bellows-pedals, so that the footboard thereof when released will drop out a little way and then may be easily and slowly brought down to its lowest position by the foot of the operator.

With these objects in view my invention consists in the construction and combinations of parts, as hereinafter described and claimed.

In the accompanying drawings, Figure 1 is a side view of a portion of a piano with the end casing removed, showing my improvement. Fig. 2 is a front view of a part thereof, showing the pedals and counterbalancing-spring. Fig. 3 is a side view, on an enlarged scale, of the self-playing attachment when opened. Fig. 4 is a section on the line 4 4 of Fig. 5. Fig. 5 is a cross-section thereof on the line 5 5 of Fig. 4. Fig. 6 is a central section showing the means for preventing the lever *p* from falling too far; and Fig. 7 is an end view of the same looking in the direction of the arrow on Fig. 6.

a represents the pneumatic box; *b*, the bellows; *c*, the spring for moving the bellows, and *d* the footboard hinged to the piano-frame at *e*, all these parts being of the usual type. The footboard is normally locked in position by means of a catch *f*, which engages in a recess *g* of the footboard, said catch being carried by a rod *h*, which rod is normally held in its uppermost position, so that the catch *f* will engage with the footboard by means of a spring *i*. *j* represents a rod for lowering the rod *h*, provided with a handle *k*. The inner end of the rod *j* is bent at right angles, and this angled portion en-

gages the top of the rod *h*, so that by turning the handle *k* the rod *h* is forced down, thus disengaging the catch *f* from the footboard.

To the lower end of the bellows is attached a link *l*, the other end of which is attached to the lower end of the bell-crank lever *m*, the upper end of which is supported by a fixed pivot *n*. To the bell-crank lever *m* at the point *o* is pivoted the short arm of a second bell-crank lever *p*, which is provided with a roller *q* on its outer end. The parts *m* and *p* are so arranged that they slightly overlap at their lower extremities, so that when folded out, as shown in Fig. 3, the long arm of the lever *p* and the short arm of the lever *m* form a straight line, making them practically a continuous lever when in that position.

The part *m* is provided with a projection *m^a*. The lever *p* is cut away, as shown at *p^a*, and is arranged to fit against the projection or cross-piece *m^a*. This prevents the lever *p* from falling too far beyond the position shown in Fig. 3.

r represents the pedals for the self-playing attachment. The outer ends of these pedals are pivoted on rods *s*, held by fastenings *t* on the top of the footboard *d* when the same is folded out. *u* represents a shaft carried by brackets *v* on the front part of the lower end of the pneumatic box *a*, and this shaft is fixed by means of the pin *w*, which passes through said shaft and one of the brackets thereon, although it is capable of adjustment therein. *x* represents a pulley loosely mounted on the shaft *u*, and to the outer face of this pulley is fixed a flat flexible band *y*, which is attached at the point *z* to the front of the footboard *d* in the center thereof. A flat coiled spring *3* is fastened to the shaft *u* at one end and to the pulley *x* at the other end. For convenience in manufacture one head of the pulley is removable, as shown in Fig. 5, and is fastened to the body of the pulley by screws. It is obvious that the spring *3* will wholly or partially overcome the influence of gravity on the footboard *d* when the latter is released, and by adjusting it to the proper tension it may be made to resist the action of gravity on said footboard and the connected parts to any desired extent.

Having thus described my invention, what

I claim as new, and desire to secure by Letters Patent, is—

1. In a self-playing piano, the combination with the piano-frame, of a hand-lever pivoted to the front of said frame, a footboard hinged to said frame, means for locking said footboard, connections whereby the movement of said hand-lever unlocks said footboard, and means adapted to move said footboard outward when it is unlocked, substantially as described. 5
2. In a self-playing piano, the combination with the piano-frame, of a footboard normally held up against said frame, means for counterbalancing said footboard, and means adapted to throw said footboard outward, when it is unlocked, against the action of the counterbalancing means, substantially as described. 15
3. In a self-playing piano, the combination with the piano-frame, of a footboard hinged thereto, means for locking said footboard against said frame, means for counterbalancing said footboard and a spring for forcibly throwing said footboard outward a short distance after it has been unlocked, substantially as described. 25
4. In a self-playing piano, the combination of the frame thereof, a footboard hinged to said frame, means for locking said footboard to said frame, pedals pivoted to said footboard at one end, connections between the other end of each of said pedals and the frame of the piano, a spring associated with said footboard, and adapted to resist the downward movement of said footboard, and a spring adapted to force said footboard outwardly until it is resisted by said first-named spring, substantially as described. 35
5. In a self-playing piano, the combination of pneumatic devices, a movable footboard carrying pedals, transmission devices between said pedals and said pneumatic devices for operating the latter, a lock securing said footboard against the piano-frame, said pneumatic devices including means for swinging said footboard outwardly and re- 40
- silient means resisting the action of gravity on said swinging footboard when it is unlocked and swung out, substantially as de- 50
- scribed. 55
6. In a self-playing piano, the combination with the piano-frame, of a footboard normally held up against said frame, means for resiliently resisting the action of gravity on said footboard when it is unlocked, and means adapted to throw said footboard outward, when it is unlocked against the action of the resisting means, substantially as described. 60
7. In a self-playing piano, the combination with the piano-frame, of a footboard normally held up against said frame, means for counterbalancing said footboard, and means for positively throwing said footboard outward, when it is unlocked, against the action of the counterbalancing means, substantially as described. 65
8. In a self-playing piano, the combination with the piano-frame, of a footboard hinged thereto, means for locking said footboard against said frame, means for counterbalancing said footboard, and a spring for forcibly throwing said footboard outward a short distance after it has been unlocked, 70 substantially as described. 75
9. In a self-playing piano, the combination of pneumatic devices, a movable footboard carrying pedals, connections between said pedals and said pneumatic devices for operating the latter, a lock securing said footboard against the piano-frame, means for swinging said footboard outwardly, and resili- 80
- ent means resisting the action of gravity on said swinging footboard when it is unlocked and swung out, substantially as de- 85
- scribed. 85

In testimony whereof I affix my signature in presence of two witnesses.

ERNEST J. KNABE, JR.
